UNITED STATES PATENT OFFICE.

EDWARD BOEHM, OF WOODBURY, NEW JERSEY.

ARTIFICIAL STONE.

SPECIFICATION forming part of Letters Patent No. 569,002, dated October 6, 1896.

Application filed March 21, 1896. Serial No. 584,256. (No model.)

To all whom it may concern:

Be it known that I, EDWARD BOEHM, a citizen of the United States, residing at Woodbury, in the county of Gloucester and State 5 of New Jersey, have invented certain new and useful Improvements in Artificial Stone, of which the following is a specification.

My invention relates to a new and useful improvement in building-blocks, and has for 10 its object to provide a block of this description which may be applied to a frame building, giving the effect of a stone or brick building, and which also may be used for inside tiling and be applied to the wooden surfaces 15 of interior walls to produce the desired effect.

With these ends in view my invention consists in the details of construction and combination of elements hereinafter set forth, and then specifically designated by the claims.

20 In order that those skilled in the art to which this invention appertains may understand how to make and use the same, I will describe its construction and operation in detail, referring by letter to the accompanying 25 drawings, forming a part of this specification, and in which—

Figure 1 is a perspective of a section of a wooden surface having a number of my improved blocks applied thereto; Fig. 2, a horizontal section thereof, and Fig. 3 a vertical section thereof.

In carrying out my invention I provide a number of blocks A, which are preferably molded of terra-cotta or other suitable material into the shape adapted to give the desired effect, and each of these blocks when completed is provided with a groove B in one of its edges, a tongue C upon the opposite edge, a semidovetail groove D upon the inner side of one of the edges at right angles to the tongue and groove, and a semidovetail flange E upon the inner side of the opposite edge. Upon the edge of the block which is provided with the tongue a ledge F is formed, 40 of sufficient width to accommodate the holes formed therethrough for the passage of the screws G, and these screws serve the purpose of securing the block to the surface H.

To face a wooden surface with blocks made

in accordance with my improvement, it is only 50 necessary to start from the proper corner of said surface and, after securing the first block in place by the screws so that the underlapping flange E and groove B will be exposed, the next block in either the horizontal row 55 or the vertical tier is secured in place by matching its proper edge to either the groove or the flange and the insertion of the screws. This process is continued until the entire surface is covered, when the effect will be that 60 of a solid-built wall of the material which the blocks represent.

In forming the blocks I prefer to reduce their weight so far as possible by hollowing out the under side, which will lessen the strain 65 put upon the screws in holding the blocks in place.

One of the principal advantages of my improvement is that the blocks are firmly secured in position by the use of but few screws 70 for each block and that no cement or other joining material is necessary, yet when a surface is completely covered by these blocks the latter will be so interlocked with each other as to form a perfectly-rigid surface, and in 75 practice a surface may be covered with but little labor and by persons of little experience, consequently materially reducing the cost of such work.

While I have shown the blocks formed in 80 squares and representing rough-hewn stone, it is obvious that any shape might be given to these blocks, as well as a surface representing any building material; and for inside work, such as tiling, this surface would preferably be plain or slightly projecting ornamentation.

Having thus fully described my invention, what I claim as new and useful is—

1. A building-block consisting of a body 90 having a tongue and groove formed upon two opposite sides thereof, a semidovetail groove formed on the inner part of the third side, and a semidovetail flange formed on the inner part of the fourth side, as and for the 95 purpose described.

2. A building-block consisting of a molded representation of stone having a tongue and

ledge on one side, a corresponding groove and flange on the opposite side, said ledge having apertures to receive screws, a semidovetail groove formed on the inner edge of the third side and a corresponding semidovetail flange formed on the inner edge of the fourth side, as and for the purpose described.

In testimony whereof I have hereunto affixed my signature in the presence of two subscribing witnesses.

EDWARD BOEHM.
